UNITED STATES PATENT OFFICE.

OSCAR F. BOVIER, OF ITHACA, NEW YORK, ASSIGNOR OF ONE-HALF TO
JUDSON A. ELSTON, OF SAME PLACE.

CARRIAGE-PROTECTOR.

SPECIFICATION forming part of Letters Patent No. 576,991, dated February 9, 1897.

Application filed January 8, 1896. Serial No. 574,778. (No model.)

To all whom it may concern:

Be it known that I, OSCAR FRANKLIN BOVIER, a citizen of the United States of America, residing at Ithaca, in the county of Tompkins and State of New York, have invented and produced a new and original Device to Protect Carriages from the Effects of Light, Dust, and Moisture, of which the following is a specification.

10 An explanation of the device, which I have entitled the "Champion Carriage-Protector," is given in the following specification, which sets forth the construction, adjustment, and manipulation of the same, as shown by the 15 following, viz:

My invention relates to an improvement in carriage-protectors, and particularly to that class which are bodily supported above the carriage and provided with means for raising 20 one or more sides or the whole protector bodily in removing it from carriages.

The object of the invention is to so construct such a protector that to remove or insert a carriage one end of the protector may 25 be quickly and completely raised without interfering with the remainder of the protector, or at least to no greater extent than to raise the lower adjacent corners of the sides. This gives a protector which is easily manipulated, 30 and one in which the weighted lower edge or other portion of the protector cannot strike the carriage, as is frequently the case in the manipulation of those which are raised and lowered bodily.

35 Another object of the invention is to so form the protector that an end may be raised as just stated and yet be permanently connected to the sides, so that when lowered a perfectly tight union will exist between the sides and 40 ends. This is an important feature in protectors of this class, since thereby the chances for the entry of dirt and dust to the interior of the protector are reduced to the minimum.

Another object of the invention is to so construct the front end of the protector that a 45 tight joint may be made around the shafts or pole of a carriage when they are not readily removable. This special construction of the front curtain provides for materially reducing the length of the protector and thereby 50 diminishing the cost considerably from

that of those which are made long enough to take in the shafts or pole.

With these objects in view the invention consists in the construction and combination 55 of parts hereinafter fully described and set forth.

In the accompanying drawings, which form a part of this specification, Figure 1 represents my improved carriage-protector in perspective. Fig. 2 is a horizontal section of the same. Fig. 3 is a front elevation of the protector. Fig. 4 is a perspective view of the 60 protector, showing the end curtain raised.

It is intended to support the protector in 65 such place in the carriage-room as the carriage to be covered is generally stationed, and it is preferred to fix the protector there by attachment to the ceiling of the carriage-room or to any other suitable overhead support. 70 For this purpose a frame, as *x*, is provided, and this is suspended by means of posts *a*. Suitable brackets, as *e*, may be employed to brace the posts and frame. This frame may be covered with any suitable material, as indicated at *d*. Flexible material, such as 75 cotton cloth, is then secured to the edges of the frame *x* and made of sufficient length to make close contact with the floor. The cloth forming the side curtains or walls is represented 80 by *s*, while the rear wall or curtain is represented by *c* and the front wall or curtain by *f*. These walls or curtains are integrally connected together at their vertical edges, and to provide for raising one of them, as the front 85 curtain *f*, without disturbing the remainder of the protector, (at least to no greater extent than to raise the lower adjacent corners of the side curtains,) vertical folds, as *z*, are formed at the junctions of the side and end curtains. 90

The protector may be made sufficiently long to cover in the carriage and its shafts or pole, but I prefer to make it only long enough to cover the carriage. Then to provide for dropping the front curtain to the floor I make vertical divisions therein for the accommodation of the carriage shafts or pole. I have shown herein one division, as at *c*, centrally located for the accommodation of the carriage-pole. Obviously for the accommodation of carriage-shafts there would be two divisions, one at 95 each side of the middle of the curtain. 100

To provide for raising the curtain *f*, I locate along its edge suitable lips or eyes *n*, through which are passed or threaded the raising-cords *r*. In the case of an entire or undivided front 5 curtain these cords will be attached to the lower corners of the curtain and their upper ends will be passed through pulleys suitably supported above the curtain and returned, preferably, through a gripping-pulley located 10 at *u*. When the curtain is divided, as shown, the cords *r* will pass through small pulleys *p*, located at the corners of the divisions, as indicated in Fig. 3, and through loops or eyes 15 along the inner edges of said divisions up to a suitable stay, as *w*, located in a fold of the curtain or in any wise secured thereto above the divisions. Then as the cords *r* are pulled the divisions of the curtains will be folded up against the stay *w*, and on further pulling of 20 the cords the entire curtain will be raised to the top of the protector.

The board *b* is shown as representing the ceiling of the stable or any strip which may be secured to the posts *a* for supporting the 25 upper pulleys *p* and the grip-pulley *u*.

It is obvious that as the front curtain is raised the folds *z* will open and allow the ascent of the curtain without disturbing the back curtain of the protector and without 30 even disturbing the side curtains if the forward folds are large enough. (See Fig. 4.)

To the lower ends of the divisions in curtain *f* I also, by preference, attach stays or slats, as *w*, to assist in dropping the curtain 35 and in forming a close joint between it and the floor. Obviously such strips or slats may also be attached to the lower edge of the side and rear end curtains, if desired.

I have shown and described the protector 40 as suspended from a frame, which in turn is suspended from suitable supports above it. Obviously the frame *x* may be supported from posts extending upwardly from the floor or laterally from the walls of the room. It is 45 preferable, however, to make these supports as shown, as there is then no danger of disarranging the protector or its support by care-

lessly handling a carriage in running it under the protector or removing it therefrom.

Other changes than those above suggested 50 may be made in the construction and manner of support for the protector without departing from the spirit of my invention.

What I claim as my invention is—

1. A carriage-protector suitably supported 55 out of engagement with the carriage and provided with an end integral with the sides and yet adapted to be raised to its full height independently of the remainder of the protector, substantially as set forth. 60

2. A carriage-protector suitably supported out of engagement with the carriage and having its side and end walls or curtains made of flexible material and united at the vertical edges by vertical folds, one of said curtains 65 being provided with means for raising it independently of the other curtains as and for the purpose set forth.

3. A carriage-protector supported out of engagement with the carriage and having a vertically-movable front curtain integral with the side curtains and vertically movable independently of the side curtains and divided at its lower end for the accommodation of carriage shafts or pole, a stay extending across 70 the curtain above said division, and cords for raising said curtain run through suitable loops or guides around the sides and lower ends of the divided portions and along the sides of said curtain, substantially as and for 75 the purpose set forth.

4. The combination with the suspended supporting-frame of the cover *d*, the side and end walls or curtains hung from said frame and provided with the folds *z*, at the junctions between them, and raising-cords attached to one of the said curtains only and passing over suitable pulleys above it, substantially as set forth. 85

OSCAR F. BOVIER.
